(74) Attorney, Agent, or Firm—Marshall A. Lerner, Esq.; Bradford E. Mattes, Esq.; Finn T. Simmensen, Esq.

(57) **CLAIM**

The ornamental design for a battery, as shown and described.

DESCRIPTION

FIG. 1 is a perspective view of the battery showing my new design;

FIG. 2 is a perspective view of the rear thereof;

FIG. 3 is a front elevational view thereof;

FIG. 4 is a left elevational view thereof;

FIG. 5 is a rear elevational view thereof;

FIG. 6 is a top plan view thereof; and,

FIG. 7 is a bottom view thereof.

Broken lines in the figures are for illustrative purposes only and form no part of the claimed design.
